UNITED STATES PATENT OFFICE.

FRANK KRAMER, OF SEATTLE, WASHINGTON, ASSIGNOR OF THIRTY-FIVE ONE-HUNDREDTHS TO DALE C. BOICE, OF SEATTLE, WASHINGTON.

ASSORTING APPARATUS.

1,104,993.

Specification of Letters Patent. Patented July 28, 1914.

Application filed June 18, 1913. Serial No. 774,391.

To all whom it may concern:

Be it known that I, FRANK KRAMER, a citizen of the United States of America, and a resident of the city of Seattle, in the county 5 of King and State of Washington, have invented certain new and useful Improvements in Assorting Apparatus, of which the following is a specification.

The present invention relates to apparatus 10 of the above character especially adapted for assorting different lengths of lumber and it has for an object the provision of a novel construction which will operate in an efficient manner.

Another object resides in providing a 15 novel means for removing the assorted lumber from the bins in which it has been deposited.

Other objects will appear as the description progresses and those features of construction, arrangements and combinations of parts on which protection is desired, succinctly defined in the annexed claims.

Referring to the drawings, wherein like 20 characters of reference indicate like parts throughout:

Figure 1 is a plan view of an assorting apparatus embodying my invention. Fig. 2 is a side elevation thereof illustrating a plurality of assorting apparatus employed for different grades of lumber. Fig. 3 is an end elevation thereof. Fig. 4 is a sectional view taken along line 4—4 of Fig. 2. Fig. 5 is a section on line 5—5 of Fig. 1. Fig. 6 is an 25 enlarged view of the vertical adjusting mechanism for the bottom of the bin, and Fig. 7 is a cross section on line 7—7 of Fig. 1, disclosing more clearly the guideway for the conveyer and assorting chains.

Referring more in detail to the drawings, 30 1 designates a supporting frame structure, 2 shafts thereon, 3 sprockets carried on the shafts and 4 spaced conveyer chains which take over the said sprockets.

Interposed between the conveyer chains 4 35 are spaced assorting chains 5 lying in a common plane and taking over sprockets 6 carried on one of the shafts 2. These assorting chains 5 take over a respective sprocket 40 7 on the stub shafts 8 and are of different lengths varying from the shortest chain adjacent one conveyer chain 4 to the longest chain contiguous the other of said conveyer chains. The chains run in grooves 9 of supporting bars 10 which prevent the chain 45

from sagging and tend to decrease any tendency for vibration, as is obvious. The pieces of lumber are fed from chains 11, supported on sprockets 12 of one of the shafts 2, to the conveyer and assorting chains from 50 which the pieces are deposited according to lengths into their respective bins 13. The bins are made adjustable in size, to accommodate different widths of lumber, by their walls engaging and coöperating with the 55 threaded members 14. Anti-friction rollers 15 are disposed in the bottom of each bin for supporting the lumber and facilitating the removal of the latter from the bin.

Transverse chains 16 are supported on 60 sprockets 17 of shafts 18 to operate in the bins longitudinally thereof and above the rollers 15 a sufficient distance to permit of a plurality of boards or pieces of lumber being deposited prior to any operation tending 65 to remove the same.

Reference numeral 19 indicates a plurality of dogs carried by chains 16, said dogs having inclined faces 20 adapted for engagement with the uppermost board in the bin to exert a pressure thereon for increasing the friction between the piled assorted boards. Upon further movement of chains 16 and dogs 19 the boards in the bins are removed 70 to a suitable place of deposit, as, for instance, other conveyer chains 21, from which the bundles may be tied and disposed of as 75 is apparent.

As shown clearly in Fig. 2, a plurality of assorting apparatus are arranged in superposed relation. By this construction, lumber of different grades may be removed 80 from chains 11 and deposited on the inclined chains 11' taking over sprockets 22 and 12 of shafts 23 and 2 respectively. From these 85 chains 11' the lumber is disposed of in a manner similar to that described above. Chains 11' may be provided with dogs 24 to retain the pieces of lumber thereon.

The different shafts are operatively connected with a source of power supply, as 90 is apparent.

The bottom of each bin is adjustably mounted whereby different thicknesses of lumber may be assorted with the same 100 mechanism at different times, and the same number of pieces deposited in each bundle. For instance, if it is desired to assort lumber one inch in thickness, the bottom will be elevated, while for two inch thicknesses 105 110

of lumber, the bottom of the bin will be lowered. Each bottom 13' of the bins is provided with depending threaded stems 25 disposed adjacent each terminal of said bottom and receives a spiral gear 26 retained from vertical movement by the yoke 27 carried by the frame of the mechanism. Spiral gears 26 mesh with similar gears 28 carried on shafts 29 which through bevel gearing 30 are operable in common with the transverse shafts 31.

In operation, the lumber is placed on chains 11 so as to rest on the extreme left chain, when viewing the structure as illustrated in Fig. 1, whereby the left end portion of every piece of lumber will be transferred to the left conveyer chain 4 while the right end portion will be delivered to the assorting chains 5 and the right conveyer chain 4, depending on the length of the pieces of lumber. The shortest piece of lumber to be assorted would be deposited in the first bin by the right end of the lumber riding off the shortest chain 5 and, 25 being unsupported by any other assorting chain 5, tilts, thereby causing the left end portion to slide or drop from the left conveyer chain 4 into the bin. A piece of lumber to be deposited in the fourth bin, for instance, 30 would be of sufficient length to ride on the left conveyer chain 4 and the fourth assorting chain 5 (counting from the left conveyer chain). A predetermined number of lumber pieces having been deposited in a 35 bin, the uppermost piece of the stack or pile is engaged by the inclined face 20 of a dog 19 to effect a wedging action between the pile and the chain which increases the friction between the pieces of the pile sufficiently to effect movement of the latter 40 with the dog.

Having thus described my invention, what I claim as new, and desire to secure by Letters Patent of the United States of America, is:—

1. In an assorting machine, a frame, a bin having an adjustable bottom, and means mounted on the frame for movement in the bin to remove lumber therefrom.

2. In an assorting machine, a frame, a bin having an adjustable bottom, and means mounted on the frame for movement in the bin to remove lumber therefrom, said means being spaced from the bin bottom to permit of the lumber pieces being deposited on the latter, and said bin bottom being adjustable toward and from the aforesaid means.

3. In an assorting machine, a frame, a plurality of bins each having an adjustable bottom, and means for simultaneously adjusting the bottoms of the bins.

4. In an assorting machine, a frame, a bin thereon, means adapted for removing the lumber from the bin after a pre-deter-

mined amount of lumber has been deposited in the bin, and means for operating the aforesaid means.

5. In an assorting machine, a frame, assorting means thereon, and bins for receiving the assorted lumber, one wall of each bin being adjustably mounted.

6. In an assorting machine, a frame, assorting means thereon, bins for receiving the assorted lumber, one wall of each bin being adjustably mounted, and means for adjusting the walls of the bins.

7. In an assorting machine, a frame, assorting means thereon, bins for receiving the assorted lumber, one wall of each bin being adjustably mounted, and means for simultaneously adjusting the walls of the bins.

8. In apparatus of the character described, a supporting frame, a bin thereon, anti-friction means for supporting the lumber in the bin, a chain, means supporting the chain for movement in the bin above the supporting means, a dog on the chain adapted for engagement with the lumber in the bin for removal thereof, and means for operating the chain.

9. In apparatus of the character described, a supporting frame, a bin thereon, anti-friction means for supporting the lumber in the bin, a chain, means supporting the chain for movement in the bin, a dog on the chain provided with an inclined face for engagement with the lumber in the bin for removal thereof, and means for operating the chain.

10. In apparatus of the character described, a supporting frame, a bin thereon, means for exerting pressure on the pieces of lumber in the bin, means supporting the aforesaid means for movement, and means for moving the supporting means.

11. In apparatus of the character described, a supporting frame, a bin thereon, anti-friction means in the bin for supporting lumber, means for increasing the friction between the pieces of lumber supported, said last named means engaging one of the pieces of lumber, means supporting the last named means for movement, and means for operating the supporting means for the last named means.

12. In apparatus for the character described, a supporting frame, a bin thereon, anti-friction means in the bin for supporting lumber, means for exerting pressure on the pieces of lumber in the bin, means supporting the aforesaid means for movement, and means for moving the supporting means.

13. In apparatus of the character described, a supporting frame, a bin thereon, a chain supported above the bottom of the bin to permit of lumber being deposited on the bin bottom, means on said chain for removing the lumber from the bin, and means for operating the chain.

14. In apparatus of the character described, a supporting frame, a bin thereon provided with an adjustable bottom, means for adjusting said bottom, and means for removing the pieces of lumber supported by the bottom after a predetermined number of such pieces have been deposited thereon.

15. In a machine of the character described, a frame, means for supporting lumber, means for exerting pressure on the pieces of lumber supported on the first means, and means for moving the second means to convey the lumber.

16. In a machine of the character described, a frame, adjustable supporting means for lumber, and means for exerting

pressure on the pieces of lumber supported to remove the same.

17. In a machine of the character described, a frame, adjustable supporting means for lumber, means for exerting pressure on the pieces of lumber supported to remove the same, and means to adjust the supporting means toward and from the second means.

Signed at Seattle, Washington, this 31st day of May 1913.

FRANK KRAMER.
